UNITED STATES PATENT OFFICE.

ROBERT TUERCK, OF ZURICH, SWITZERLAND, ASSIGNOR TO EUGEN GUHL, OF ZURICH, SWITZERLAND.

CLOCK STRIKING MECHANISM.

SPECIFICATION forming part of Letters Patent No. 755,260, dated March 22, 1904.

Application filed November 28, 1902. Serial No. 133,171. (No model.)

To all whom it may concern:

Be it known that I, ROBERT TUERCK, a subject of the Emperor of Germany, and a resident of Zurich, Switzerland, have invented 5 certain new and useful Improvements in Striking-Clocks, of which the following is a specification.

My invention has relation to striking mechanisms for clocks organized to strike the hours 10 and half-hours.

Generically the invention consists in the combination, with a striking mechanism, means to lock the same against operation, and a let-off mechanism comprising a let-off lever, of means 15 to control the movements of said lever, consisting of a step-disk in the form of a star-wheel having twelve teeth and provided with a stop serving to arrest the movements of the let-off lever after the hour has been struck, 20 said stop constituting the starting-point from which the star or step wheel, hereinafter called the "step-wheel," is moved, and to which it is returned through the instrumentality of the let-off lever during the striking of the hour. 25 The step-wheel has motion with the minute-hand and also with the hour-hand, the movement of the step-wheel to its starting-point being in a reverse direction.

The invention further consists in the provision of means for actuating the let-off lever and releasing the striking mechanism at each 30 half-hour in such manner as to prevent said lever from impacting a backward movement to the step-wheel.

35 The invention further consists in details of construction and combinations of co-operating parts, as will now be fully described, reference being had to the accompanying drawings, in which—

40 Figure 1 is a sectional rear elevation of so much of a clock-striking mechanism as will be necessary to an understanding of my invention, the elements thereof being shown in their relative positions after the striking of 45 the half-hour. Fig. 2 is a similar view showing the elements in their relative positions just before striking the hour. Fig. 3 is a plan view of Fig. 2. Fig. 4 is a detail view. Fig. 5 is a sectional fragmentary front elevation

showing the elements in their relative positions when striking the hour. Fig. 6 is a sectional front elevation showing the elements in their relative positions after striking the hour, and Fig. 7 is an end elevation of Fig. 6.

In the drawings, *p* and *p'* indicate the front 55 and rear frame-plates for the striking and time trains, only so much of either being shown as will be necessary to an understanding of my invention.

1 indicates the hammer-actuating pin-wheel, 60 having pins 2, adapted to engage a radial arm 4 on the hammer-shaft 3 and rock the latter in a well-known manner, and to said shaft 3 is secured the rod which carries the hammer 5. The pin-wheel 1 is geared to an arbor 6, 65 which latter is driven to make one complete revolution for each stroke of the hammer, and to said arbor 6 are secured a sectoral cam 27 and a radial arm 7, having a pin 8 at its free end adapted to be engaged by a pallet 10 on a detent-arm 9, secured to one end of a shaft 12, to the opposite end of which is secured a let-off 70 lever 13, the downward movement or drop of which is limited by a stud 13' on the front frame-plate *p*, said shaft 12 being secured in 75 bearings formed in radial arms 11 on the hammer-shaft 3, so that when said shaft is rocked the detent 9 and lever 13 are reciprocated, while said detent and lever have also a rocking motion with the hammer-shaft. At its free end 80 the lever 13 has a laterally-projecting pin 14, on which is loosely mounted a weighted disk 15, having a radial arm carrying a laterally-projecting pin 16 and a pallet 15', and said disk has two pins 18 and 18', one above and 85 the other below the let-off lever 13, the pin 18' serving to limit the downward swing of the disk 15 under its weight, while pin 18 serves to lock said disk to the let-off lever and cause the two to move in an upward direction 90 under the action of the let-off cam presently to be described, the relative location of said pins 18 and 18' being such that the disk will have a certain amount of idle angular movement on its pin 14 when rotated positively in 95 one direction or by gravity in an opposite direction.

On the minute-hand arbor *a* is secured a let-

off cam 17, having a laterally-projecting pin 17' at about the point of junction of the cam-nose 20 with the part 26 of greater diameter of said cam, and on said minute-hand arbor 5 is frictionally mounted, so as to rotate therewith, a step-wheel 21 having twelve teeth, the gap between two of which is bridged over by a bridge 22. The step-wheel 21 has a laterally-projecting pin 23 in the path of a like 10 pin 25 on the hour-wheel 24, whereby the rotation of the step-wheel with the minute-hand arbor is arrested and said step-wheel caused to move synchronously with the hour-wheel whenever the pin 23 overtakes the pin 25.

15 The operation of the described striking mechanism is as follows: At the stroke of the hour or at the last stroke of the hour the pin 14 on let-off lever 13 is caught by the bridge 22 on step-wheel 21, the cam 17 and weighted disk 15 then occupying the relative positions shown in Fig. 6, while the relative position of or the distance between the pin 25 on hour-wheel 24 and the pin 23 on step-wheel 21 will depend upon the hour to be struck.

20 Inasmuch as the let-off lever 13 and detent 9 are rigidly connected to the hammer-shaft 3 and inasmuch as the hammer-shaft is locked against rotation by detent-pallet 10 and pin 8 of radial arm 7 on arbor 6, the detent-lever is 25 held against motion or in a normal position. Starting from the position shown in Fig. 6, as the minute-hand arbor *a* is about to complete one-half of a revolution the nose 20 of let-off cam 17 impinges on pin 16 of weighted disk 30 15, turning the same idly in a direction opposite to the direction of rotation of the said arbor *a* until pin 18 on said disk contacts with let-off lever 13, thus locking the two together and causing the said lever, and with it the detent 40 9, to be lifted by the cam-nose 20 sufficiently to move the detent-pallet 10 out of engagement with pin 8, allowing arbor 6 to rotate, whereby the sectoral cam 27, acting on said detent 9, lifts the same, and with it the let-off 45 13, still higher. The sectoral arm 27 then moves out of contact with detent 9, allowing the same and the let-off lever 13 to drop, and thereby rocking the hammer-shaft 3, causing the hammer to strike the sounding device, 50 50 whereby pallet 10 is brought into the path of pin 8 and locks the striking mechanism. As soon as cam-nose 20 clears pin 16 on disk 15 to allow let-off lever 13 to drop said disk swings back to a normal position and its pin 55 is caught by the part 26 of greater diameter of the let-off cam, thus limiting the drop of detent 9 and preventing disengagement of pallet 10 from its pin. Before the minute-hand arbor completes its revolution the pin 23 on 60 step-wheel 21 will overtake the pin 25 on hour-wheel 24, causing said step-wheel to move with said hour-wheel until the latter has made one-twelfth of a revolution, at which time the minute-hand arbor *a* and let-off cam 17 will 65 have made a complete revolution, thereby

bringing cam-nose 19 of cam 17 in contact with pin 16 on disk 15, whereby said disk is turned, as before, in a direction opposite to the hands of the clock to lock the disk to the let-off lever, and thereby lift the same, and therewith the detent 9, to release the striking mechanism. As the let-off lever is lifted and allowed to drop at each revolution of the sectoral cam 27 on arbor 6, the pin 14 on said let-off lever acting on the teeth of the step-wheel 70 75 80 85 90 95 100 105 110 115 120 125 130 21 moves the same back a distance of one tooth for each stroke of the hammer until at the last stroke the bridge 22, then lying under pin 14 on let-off lever, will so limit the downward movement of said lever as to bring the detent-pallet 10 in the path of pin 8, and thus lock the striking mechanism. In the striking of the hour as soon as cam-nose 19 moves out of contact with pin 16 on disk 15 the latter swings down behind said cam-nose, and the lever 13 now drops onto the part 28 of least diameter of the cam 17, or, in other words, the lever 13 moves down to a greater extent than during the striking of the half-hour, and as the detent-arm 9 partakes of this movement it will lie below pin 8 on arm 7 when in its lowermost position, and to admit of the passage of said pin the arm 9 is provided with the recess 9', as shown in Fig. 3. On the other hand, as has been stated, the let-off lever 13 and detent-arm 9 are so connected with the hammer-shaft as not only to partake of its rocking motion, but also to receive a reciprocating motion, the recess 9' being so located as to lie in the path of pin 8 on arm 7, secured to arbor 6 at the proper moment, while the reciprocations of lever 13 are necessary to the proper step-by-step backward rotation of step-wheel 21. In Fig. 2 the sectoral cam 27 is shown as about to move out of engagement with detent-arm 9, the latter being at the limit of its upward movement as well as at the limit of its rectilinear or substantially rectilinear movement to the right. As the detent is released by the cam 27 said detent-arm, the hammer, and the let-off lever drop, while the latter lever and the detent-arm at the same time move toward the left, so that when the parts are in the position shown in Fig. 5 the recess 9' in detent-arm 9 will lie under pin 8 on radial arm 7, while pin 14 on let-off lever 13 not only exerts a downward pressure on a tooth of step-wheel 21, but also moves along the same to clear it. Obviously the period of contact of the pins 23 and 25 on step and hour wheels, respectively, depends on the angular backward movement of said step-wheel, which varies every hour from one-twelfth to substantially a complete revolution, and inasmuch as the hour-wheel makes one-twelfth of a revolution for each complete revolution of the minute-hand arbor and in view of the fact that the contact between the two pins takes place and the step-wheel 21 is thereby caused to move with the hour-wheel 24 an additional

angular movement equal to one-twelfth of a revolution of said step-wheel is imparted to it at each succeeding hour from one to twelve. In Fig. 5 the clock is striking five, 5 the wheel 21 being turned back a distance of five teeth, when the bridge 22 will stop the striking. During the next hour and before the step-wheel 21 has moved with the minute-hand arbor a distance but slightly greater than 10 that between five teeth its movement will be arrested by the hour-wheel and said step-wheel will then move with said hour-wheel, and as the latter will have made one-twelfth of a revolution when the minute-hand arbor completes 15 its revolution the step-wheel will have been advanced one step more—i. e., there will be six teeth between the bridge 22 and the pin 14 on let-off lever 13, and so on for each hour.

I have described the weighted disk 15 as 20 being provided with a pallet 15' and the let-off cam 17 as being provided with a pin 17' about at the point of junction of the cam-nose 20 with the portion 26 of greatest diameter of said cam. From the description of the opera- 25 tion of the striking mechanism it will readily be seen that the pin and pallet referred to do not affect the said operation in any manner and may therefore be dispensed with. It is obvious, however, that the action of the pin 17' on pallet 15' at a time when pin 16 lies in 30 the angle formed by the cam-nose 20 and the convex part 26 of cam 17 will facilitate the passage of pin 16 onto said convex portion in that the pin 17' will then support the weight 35 of disk 15.

Having thus described my invention, what I claim as new therein, and desire to secure by Letters Patent, is—

1. In a clock having hour and half-hour striking mechanism, the combination of a minute-arbor, a twelve-tooth ratchet or step-wheel controlling the hour-striking work, loosely mounted on said arbor so as to normally rotate with it through friction and having the 40 gap between two teeth bridged over, and provided with a lateral stop, an hour-wheel having a stop which engages said stop of the ratchet-wheel and carries the latter with it, a hammer-striking mechanism, a releasing-lever carried by the hammer-shaft, means for imparting a reciprocating motion to said lever, means for imparting an up-and-down motion to the same, and a pin projecting from said releasing-lever end and engaging with the 45 teeth of said ratchet-wheel, whereby the latter is given a retrograde motion, tooth by tooth, until the pin rests upon the said bridge and so stops the striking, all substantially as described.
2. In a clock having hour and half-hour striking mechanism, the combination of a minute-arbor, a twelve-tooth ratchet or step-wheel controlling the hour-striking work, loosely mounted on said arbor so as to normally rotate with it through friction, and having the 50

gap between two teeth bridged over, and provided with a lateral stop, an hour-wheel having a stop which engages said stop of the ratchet-wheel and carries the latter with it, a hammer-striking mechanism, a releasing-lever 70 carried by the hammer-shaft, means for imparting a reciprocating motion to said lever, means for imparting an up-and-down motion to the same, and a pin projecting from said releasing-lever end and engaging with the 75 teeth of said ratchet-wheel, whereby the latter is given a retrograde motion tooth by tooth until the pin rests upon the said bridge and so stops the striking, a cam-disk having two projections mounted on the minute-arbor, a weighted sleeve loosely mounted on the releasing-lever pin and having a pin traveling 80 on the surface of said cam and engaging at each half-hour with the projections of the cam-disk, and two projections which receive between them the lower end of the releasing-lever, all substantially as described.

3. In a clock having hour and half-hour striking mechanism, the combination of a hammer-shaft, means for operating the same, 90 cranks on said shaft, an arbor carried by said cranks, a releasing-bar having a pin at its lower extremity mounted at one end of said arbor, a stop-lever mounted at the opposite end of said arbor, a pinion-shaft, means for 95 rotating same once at each stroke, an arm projecting from said pinion-shaft and adapted to be engaged by the stop of the stop-lever, a cam mounted on said pinion-shaft for raising said stop-lever, a minute-arbor, a twelve-tooth 100 ratchet or step-wheel controlling the hour-striking work, loosely mounted on said arbor so as to normally rotate with it through friction, and having the gap between two teeth bridged over, and provided with a lateral stop, 105 an hour-wheel having a stop which engages said stop of the ratchet-wheel and carries the latter with it, a releasing-lever carried by the hammer-shaft, means for imparting a reciprocating motion to said lever, means for imparting an up-and-down motion to the same, and a pin projecting from said releasing-lever end and engaging with the teeth of said ratchet-wheel, whereby the latter is given a retrograde motion tooth by tooth until the pin 110 rests upon the said bridge and so stops the striking, a cam-disk having two projections mounted on the minute-arbor, a weighted sleeve loosely mounted on the releasing-lever pin and having a pin traveling on the surface 115 of said cam and engaging at each half-hour with the projections of the cam-disk, and two projections adapted to receive between them the lower end of the releasing-lever, all substantially as described.

4. The combination with the striking mechanism of a clock, a let-off lever vibrating with the hammer and means controlled by the minute-hand arbor to actuate the let-off lever and let off the striking mechanism at each revolu- 120 125 130

tion of the minute-hand arbor; of a step-wheel having twelve teeth and a stop adapted to move synchronously with the minute-hand arbor, means to cause the step-wheel to move synchronously with the hour-hand before the striking of the hour and until the minute-hand arbor completes a revolution, and means on the let-off lever to turn the step-wheel in a direction opposite to the hands of the clock 10 one-twelfth of a revolution for each hour-stroke to bring its stop in position to stop the vibration of the let-off lever and lock the striking mechanism, substantially as described.

5. The combination with the striking mechanism of a clock, a let-off lever vibrating with the hammer and means controlled by the movements of the minute-hand arbor to actuate the let-off lever and release the striking mechanism at each half-revolution of the minute-hand arbor; of a step-wheel having twelve teeth and a stop, adapted to move synchronously with the minute-hand arbor, means to cause said wheel to move synchronously with the hour-hand before the striking of the hour 20 and until the minute-hand arbor has made a complete revolution, means on the let-off lever to turn the step-wheel in a direction opposite to the hands of the clock one-twelfth of a revolution for each stroke to bring its stop in position to stop the vibration of the let-off lever and lock the striking mechanism and means to prevent this backward movement of the step-wheel when the half-hour is struck, substantially as set forth.

30 35. The combination with the striking mechanism of a clock, a let-off lever vibrating with the hammer and means controlled by the minute-hand arbor to actuate the let-off lever and let off the striking mechanism; of a control-

ling device revolute with the minute-hand arbor, means to cause said device to move synchronously with the hour-hand before the striking of the hour and before the minute-hand arbor has completed a revolution, said let-off lever adapted to impart a backward angular movement to said controlling device for each hour-stroke, and said controlling device adapted to act on the let-off lever and cause the latter to throw the striking mechanism out of operation when the hour has been 40 struck, substantially as set forth.

45 7. The combination with the striking mechanism of a clock, a let-off lever vibrating with the hammer and means controlled by the minute-hand arbor to actuate the let-off lever and let off the striking mechanism; of a controlling device revolute with the minute-hand arbor, means to cause said device to move synchronously with the hour-hand before the striking of the hour and before the minute-hand arbor has completed a revolution, said let-off lever adapted to impart a backward angular movement to said controlling device for each hour-stroke, and said controlling device adapted to act on the let-off lever and cause 55 the latter to throw the striking mechanism out of operation when the hour has been struck, and means preventing backward angular movement of the controlling device when the half-hour is struck, substantially as 60 set forth.

In testimony whereof I have signed my name to this specification in the presence of two subscribing witnesses.
